Application July 9, 1946, Serial No. 682,186

12 Claims. (Cl. 74—2)

1

This invention relates to circuit breakers and, more particularly, to tripping mechanism for tripping large circuit breakers.

Circuit breakers used in medium and high voltage alternating-current distribution systems are relatively large and considerable energy is required to operate the relatively heavy latch mechanism to trip the breakers. Circuit breakers may be tripped either from an auxiliary source of power, such, for instance, as a storage battery, or from energy derived from a current transformer. In many instances, an auxiliary source of power is not available or practical, and the practice has been to provide an alternating-current electromagnet for tripping the latch mechanism of the breaker, the electromagnet being connected in a control circuit which is energized by a current transformer coupled to the line controlled by the breaker. The inefficient use of the limited power available by the electromagnet renders such arrangements unsatisfactory, particularly for tripping large, heavy circuit breakers.

One object of the invention is to provide an improved trip device for tripping large circuit breakers, which trip device requires a minimum of energy to trip the breaker.

Another object of the invention is to provide an improved 'light-load' latching mechanism for a large circuit breaker, which latching mechanism is capable of operation by a low energy trip device to trip the breaker.

Another object of the invention is to provide a novel over-current trip device for a large, power-operated circuit breaker, wherein the tripping is effected by stored energy released by a low-energy electro-responsive means.

Another object of the invention is to provide a circuit breaker with an improved latching mechanism that is simple, reliable in operation and inexpensive to manufacture.

The novel features that are considered characteristic of the invention are set forth in the appended claims. The invention itself, however, both as to structure and operation, together with additional objects and advantages thereof, will be best understood from the following detailed description of several embodiments thereof, when read in connection with the accompanying drawings, in which:

Figure 1 is an elevational view, partly in section, of a circuit breaker embodying the principles of the invention; and

Fig. 2 is an elevational view, partly in section, of a circuit breaker showing a modification of the latch mechanism.

2

Referring to Figure 1 of the drawings, the circuit breaker 3, which is illustrated diagrammatically, may be of any conventional construction either of the oil-break, air-break or gas-blast type and, when tripped, is adapted to be operated to the open position by means of an accelerating spring 5. The circuit breaker is adapted to be operated to the closed position by means of an operating mechanism which, in the embodiment shown, comprises a compressed-gas motor of the type disclosed in Patent No. 2,384,901, issued September 18, 1945, to J. M. Cumming and Henry L. Peek, and assigned to the assignee of the instant invention. The operating mechanism in the embodiment shown includes a main casing 11 which is formed to provide an operating cylinder 13 closed at the lower end by a member 15 suitably secured to the casting 11. The upper end of the cylinder is closed by an integral part of the casting. Mounted for reciprocal movement in the cylinder 13 is a piston 17 secured to a piston rod 19. The piston rod 19 is pivotally connected by means of a pivot pin 21 to a pair of operating levers 23 and also to a breaker operating rod 25. The operating levers 23 are pivotally supported at their right-hand ends by means of a pivot pin 27 of the upper end of a link 29 whose lower end is pivoted on a pivot pin 31 mounted in a pair of spaced ears 33 (only one being shown) integral with and extending outwardly and upwardly from the main casting 11. The left-hand ends of the operating levers 23 are rigidly connected by means of a rod 35 and are spaced apart by means of a latch roller 37 rotatably mounted on the rod 35.

The breaker mechanism is releasably restrained in the closed position by means of a latching mechanism illustrated generally at 39. The latch mechanism 39 includes a main latch 41 pivotally supported on a pivot pin 43 mounted in spaced projections 45 (only one being shown) integral with and extending upwardly from the main casting 11. The main latch 41 is biased to latching position by means of a coil spring 47 coiled about a rod 49 and compressed between a projection 51 of the main casting 11 and a washer 53 supported on the lower end of the rod 49 by a nut 55. The rod 49 extends upwardly through an opening in the projection 51 and is pivotally connected by means of a pivot pin 57 to the main latch 41.

The main latch 41 is of the slip-off type and the configuration of its latching surface is such that it will not, by itself, retain the operating mechanism in the closed position. For this reason, an

auxiliary latch 59 is provided to maintain the main latch 41 in latching position. The auxiliary latch 59 is pivoted on a pin 61 supported in the projection 45 of the casting 11 and a latching nose 63 thereof is biased by means of a spring 65 into latching engagement with a tail 67 of the main latch. The auxiliary latch 59 is provided with a horizontally extending tail 69 in which is mounted, at a point near its free end, an adjusting screw 71 secured in position by means of a lock nut 73. The adjusting screw 71 is disposed in vertical alignment with the upper end of a trip rod 75 which has its lower end pivotally connected to a trip lever 77 pivotally mounted on a pivot pin 79. The pivot pin 79 is supported by and extends between a pair of spaced brackets 81 (only one being shown) rigidly mounted on the underside of the projection 51 of the main casting 11. The trip lever 77, at its pivoted end, is provided with a pair of projections 83 (only one being shown), one disposed on each side of the lever 77 and rigidly secured thereto. The projections 83 are mounted on the pivot pin 79 to pivotally support the trip lever 77 thereon.

The trip rod 75 is biased in tripping direction by means of a stored-energy device comprising a relatively strong tripping spring 85 which is compressed between the tripping lever 77 and a support lever 87. The support lever 87 comprises a pair of spaced parallel levers having an arm 89 rigidly secured between them at their right-hand ends for pivotally supporting the lever 87 on the pivot pin 79.

A rod 91 pivotally connected by means of a pin 93 to the lever 87 projects upwardly through an opening in the trip lever 77. A washer 95 surrounding the rod 91 above the trip lever and a pin 97 in the rod 91 provide a lost motion connection between the lever 77 and the lever 87. A spring guide 99 surrounds the rod 91 within the coil of the tripping spring 85.

The force of the tripping spring 85 biases the trip lever 77 in clockwise or tripping direction about the pivot pin 79, and biases the lever 87 in a counterclockwise direction about the pin 79. The lever 87 in the closed position of the breaker is restrained by the levers 23 in the position shown in Fig. 1, in order to maintain the spring 85 in compression and in readiness to trip the breaker. The free end of the lever 87 is connected by means of an adjustable connecting rod 101 to a lever 103 pivoted on the pivot pin 43 on which the main latch 41 is mounted. The right-hand end of the lever 103 is rounded and is engaged and held in the position shown by a cross member 105 rigidly connecting the parallel operating levers 23. The tripping lever 77 is normally restrained against tripping movement by means of a light-load latch 107 pivoted on a pivot pin 109 supported in the brackets 81. A horizontally extending tail 111 of the latch 109 is disposed above a trip rod 113 secured to the armature 114 of a low energy tripping electromagnet illustrated generally at 115. The armature 114 in the unattracted position rests on projecting bracket 116 of the member 15. The electromagnet 115 is supported by means of a pair of brackets 117 secured to the undersides of the brackets 81. The light-load latch 107 is biased to latching position by means of a spring 119 coiled about the pin 109 on each side of the latch and having its bight engaging the latch 107 and its ends hooked over the brackets 81.

Upon energization of the tripping electromagnet 115, upon the occurrence of an overload cur-

rent or by operation of a manual switch, the trip rod 113 is actuated upwardly and operates the latch 107 to release the trip lever 77. The trip lever 77 is immediately operated by the tripping spring 85 and moves the trip rod 75 upwardly to strike the tail 69 a hammer blow and operate the auxiliary latch 59. Operation of the auxiliary latch 59 frees the main latch 41 and permits the accelerating spring 5 to move the main latch out of the way of the latch roller 37 and to move the breaker mechanism to the open position.

The tripping movement of the trip lever 77 is limited by the washer 95 striking the pin 97 which also neutralizes the force of the spring 85. Movement of the operating lever 23 to the open position permits the lever 103 and the support lever 87 which supports the stored-energy device to rotate in a counterclockwise direction about their respective pivots. This movement is aided by means of a spring 121 surrounding the trip rod 75 and compressed between a shoulder on the trip rod and a spring seat in the projection 51 of the casting 11. The counterclockwise movement of the lever 87 acting through the rod 91 and pin 97 and assisted by the spring 121 resets the tripping lever 77 to its latched position.

As soon as the latch roller 37 is clear of the main latch 41, this latch is immediately restored to its latching position by the spring 47. If, in this position of the main latch 41, the auxiliary latch 59 were permitted to resume its latching position under the tail 67 of the main latch, it would be impossible for the latch roller 37, upon closure of the breaker, to resume its latching position relative to the main latch 41. It is, therefore, necessary to prevent movement of the auxiliary latch 59 to its latching position until after the breaker is closed and the main latch is properly engaged with the roller 37. To this end, a holding lever 123 pivoted on the pivot pin 61 is provided. The holding lever 123 is provided with a cross member 125 integral therewith and is biased by means of a spring 127 in a direction to engage the cross member 125 with the tail 69 of the auxiliary latch. The holding lever 123, in the closed position of the breaker, is prevented from engaging the auxiliary latch by engagement of the roller 37 with a cross member 129 integral with the holding lever 123.

When the operating levers 23 move in opening direction, following a tripping operation of the trip mechanism, the spring 127 moves the holding lever 123 clockwise about the pivot 61 to engage the cross member 125 with the tail 69 of the auxiliary latch 59 and holds the latch in unlatching position until the breaker is closed.

The piston 17 and the breaker mechanism is operated to closed position by admitting compressed gas to the cylinder 13 above the piston 17, which, when the breaker moved to open position, assumed a position in the upper end of the cylinder. Compressed gas is admitted through an inlet passage 131 to the cylinder by means of an electromagnetically operated inlet valve device indicated generally at 133. The inlet valve device comprises an inlet valve 135 and an exhaust valve 137 both mounted on a valve rod 139. The inlet valve 135 is biased closed and the exhaust valve 137 is biased to open position by means of a spring 141. The rod 139 is secured to an armature 143 of an electromagnet indicated generally at 145 which, when energized in a well-known manner, moves the armature 143 downwardly to open the inlet valve 135 and close the exhaust valve 137 thus admitting compressed gas

to the cylinder to move the piston 17 downwardly to close the breaker.

As the breaker nears the closed position, the latch roller 37 engages the beveled end of the main latch 41, and, since the auxiliary latch is held in unlatching position, moves the main latch 41 in unlatching direction. As soon as the roller 37 clears the nose of the main latch 41, the spring 47 restores this latch to latching position. As the roller 37 moves to its latching position, it engages the cross member 129 and moves the holding lever 123 to free the auxiliary latch 59 which is then moved by its spring 65 to latching engagement with the main latch.

As the operating levers 23 approach the closed position, the cross bar 105 engages the end of the lever 103 and rocks this lever in clockwise direction. During this movement, the lever 103, acting through the rod 101, raises the stored-energy device support lever 87, and, since the tripping lever 77 is now restrained by the latch 107, compresses the stored-energy means or tripping spring 85 in preparation for another tripping operation.

The modification of the trip mechanism shown in Fig. 2 of the drawings is shown applied to a circuit breaker of the same type as that shown in Fig. 1. Consequently like reference numerals have been applied to like parts. The trip mechanism is indicated generally at 151 (Fig. 2) and comprises a trip rod 153 having its upper end disposed beneath the tail 69 of the auxiliary latch 59 and its lower end pivotally connected to a floating trip lever 155 by means of a pivot pin 157. One end of the trip lever 155 is restrained by means of a light-load latch 159 against the bias of a stored-energy device or tripping spring 161. The latch 159 is pivoted on a pin 163 supported in the sides of a U-shaped bracket 165 secured to the projection 51 of the main casting 11 and is biased to latching position by means of a spring 167. The other end of the tripping lever 155 is restrained against movement in tripping direction by means of a restoring rod 169 the lower end of which bears against the floating lever 155 and the upper end of the rod 169 bears against and is restrained against upward movement by the cross member 125 of the holding lever 123.

The tripping spring 161 is compressed between a spring guide 171 pivotally connected to the floating trip lever 155 by a pin 173, and the yoke 175 of the U-shaped bracket 165. A spring 177 surrounding the upper end of the rod 169 and compressed between the cross member 125 of the holding lever 123 and a spring seat in the projection 51 of the main casting 11 biases the holding lever 123 to its operated position.

When the trip magnet 115 is energized, the armature 114 thrusts the trip rod 113 upwardly, striking a tail 179 on the light-load latch 159 and operating the latch to release the left hand end of the floating trip lever 155. Release of the trip lever 155 permits the tripping spring 161 to expand, rocking the trip lever 155 in clockwise or tripping direction about its point of engagement with the rod 169 as a fulcrum. This operation of the trip lever thrusts the trip rod 153 upwardly to strike the tail 69 of the auxiliary latch a hammer blow and operate the auxiliary latch 59. The tripping movement of the trip rod 153 is limited by the engagement of a shoulder 181 thereon with the projection 51 of the main casting. Operation of the auxiliary latch 59 releases the main latch 41 and permits opening of the breaker in

the previously described manner. As the roller 37 moves in opening direction, the spring 177 rotates the holding lever 123 to engage the cross member 125 with the tail 69 of the auxiliary latch 59 and hold this latch in unlatched position. Movement of the holding lever 123 and its cross member 125 permits the tripping spring 161 to expand farther and rock the floating tripping lever 155 counterclockwise about the pin 157 which is, at this time, held against movement by engagement of the shoulder 181 with the projection 51. This causes the latching end of the trip lever to reengage the latch 159.

The breaker mechanism is operated to closed circuit position by energization of the closing electromagnet 145 which operates the inlet valve mechanism 133 and admits compressed gas to the cylinder 13 in the manner previously described. As the breaker mechanism moves to closed position and the roller 37 approaches the latched position, it engages the cross member 129 of the holding lever 123 and operates this lever in a counterclockwise direction to release the auxiliary latch for the purpose set forth previously. Movement of the holding lever 123 in counterclockwise direction causes the cross member 125 to move the rod 169 downwardly rocking the floating trip lever 155 clockwise about its point of engagement with the latch 159. This compresses the tripping spring 161 to store energy therein in preparation for a subsequent tripping operation and, at the same time, moves the trip rod 153 downwardly to permit relatching of the auxiliary latch 59 with the main latch 41 to releasably restrain the circuit breaker in the closed position.

From the foregoing, it will be seen that there is provided a light-load, high-speed latching mechanism for controlling the tripping of a circuit breaker, the latch mechanism being operated by stored energy released by a light-load latch actuated by the energization of an electromagnet which requires a minimum of energy.

While the invention has been disclosed in accordance with the provisions of the patent statutes, it is to be understood that various changes in the structural details and arrangement of parts thereof may be made without departing from some of the essential features of the invention.

We claim as our invention:

1. In a circuit breaker including operating mechanism therefor, latching mechanism for releasably restraining said operating mechanism in closed position comprising a main latch, an auxiliary latch for restraining said main latch in latching position and operable to release said main latch, stored energy means for operating said auxiliary latch, means comprising a light-load latch releasably restraining said stored energy means, trip means comprising low energy electro-responsive means responsive to overload currents for operating said light-load latch to release said stored energy means, and a member automatically operated by said breaker operating mechanism during a closing operation to store energy in said stored energy means.

2. In a circuit breaker including operating mechanism therefor, latching mechanism for releasably restraining said operating mechanism in closed position comprising a main latch, an auxiliary latch for restraining said main latch in latching position and operable to release said main latch, stored energy means for operating said auxiliary latch, means comprising a light-

load latch releasably restraining said stored energy means, and trip means comprising low energy electro-responsive means for operating said light-load latch to release said stored energy means, a support member for movably supporting said stored energy means, and a part movable with said operating mechanism upon opening of said breaker to permit movement of said support member to effect relatching of said stored energy means.

3. In a circuit breaker including operating means therefor, latching mechanism for releasably restraining said operating means in closed position comprising a main latch biased to latching position, an auxiliary latch biased to latching position for releasably restraining said main latch in latching position, a trip lever operable to operate said auxiliary latch to effect release of said operating means, stored energy means for operating said trip lever, means comprising a light-load latch for releasably restraining said trip lever against tripping operation, and a trip device comprising electro-responsive means for operating said light-load latch to release said trip lever, and resetting means operated by said operating means to first effect relatching of said trip lever and then to store energy in said stored-energy means.

4. In a circuit breaker comprising operating means therefor, latching mechanism for releasably restraining said operating means in closed position comprising a main latch biased to latching position, an auxiliary latch biased to latching position for releasably restraining said main latch in latching position, a trip lever operable to operate said auxiliary latch to effect release of said operating means, stored energy means for operating said trip lever, means comprising a light-load latch for releasably restraining said trip lever against tripping operation, a trip device comprising electro-responsive means for operating said light-load latch to release said trip lever, and movable support means supporting said stored energy means and movable upon movement of said operating means in opening direction to permit relatching of said trip lever.

5. In a circuit breaker comprising operating means therefor, latching mechanism for releasably restraining said operating means in closed position comprising a main latch biased to latching position, an auxiliary latch biased to latching position for releasably restraining said main latch in latching position, a trip lever operable to operate said auxiliary latch to effect release for operating said trip lever, means comprising a light-load latch for releasably restraining said trip lever against tripping operation, and a trip device comprising electro-responsive means for operating said light-load latch to release said trip lever, and movable support means supporting said stored energy means and operable upon movement of said operating means in opening direction to permit automatic relatching of said trip lever, and means actuated by said operating means during a closing movement thereof for actuating said movable support to store energy in said stored energy means.

6. In a circuit breaker comprising power operated operating means for closing said breaker, latching mechanism comprising a main latch for engaging a part movable with said operating means to releasably restrain said operating means in closed position, an auxiliary latch for restraining said main latch in latching position and operable to release said main latch, stored-

energy means for operating said auxiliary latch, means comprising a light-load latch for releasably restraining said stored-energy, electro-responsive means operable to actuate said light-load latch to release said stored-energy means to effect operation of said latch mechanism and release of said operating means, resetting means operable upon movement of said operating means in opening direction to reset said stored energy restraining means, and a member on said operating means for engaging and actuating said resetting means to store energy in said stored energy means.

7. In a circuit breaker comprising operating means therefor, latching mechanism for releasably restraining said operating means in closed position comprising a main latch, an auxiliary latch for restraining said main latch in latching position and operable to release said main latch, holding means operable upon movement of said operating means in opening direction to maintain said auxiliary latch in non-latching position, means comprising a stored-energy device for operating said auxiliary latch, latch means for restraining said stored-energy device against operation, electro-responsive means operable when energized to release said stored-energy device to effect opening of the breaker, and means operable by said holding means when said operating means moves to closed position to store energy in said stored-energy device.

8. In a circuit breaker comprising operating means therefor, latching mechanism comprising a main latch for releasably restraining said operating means and an auxiliary latch for restraining said main latch in latching position, a trip member for actuating said auxiliary latch to release said main latch, holding means for restraining said auxiliary latch in non-latching position when the operating means is in open position, energy storing means operable when released to operate said trip member, electro-responsive means operable to release said energy storing means to effect opening of the breaker, and means operable by said holding means during a closing operation of said operating means for storing energy in said energy storing device.

9. In a circuit breaker, including operating means therefor, latch means for releasably restraining said operating means in closed position, means comprising a floating lever operable to actuate said latch means to effect opening of said breaker, energy storing means biasing said floating lever in a direction to actuate said latch means, holding means operated by the operating means in the closed position to restrain one end of said floating lever, a light-load latch normally restraining the other end of said floating lever, electro-responsive means for operating said light-load latch to release said floating lever to thereby permit said energy storing means to actuate said lever, said energy storing means acting to reengage said floating lever with said light-load latch during opening movement of said operating means, and means operated by said holding means during closing movement of said operating means to store energy in said energy storing means.

10. In a circuit breaker including operating mechanism therefor, latching mechanism comprising a main latch for releasably restraining said operating mechanism in closed position and an auxiliary latch for releasably restraining said main latch in latching position, a floating lever operable to actuate said auxiliary latch, energy storing means biasing said floating lever in trip-

ping direction, a light-load latch for releasably restraining said floating lever against tripping operation, and electro-responsive means for operating said light-load latch to release said floating lever.

11. In a circuit breaker including operating mechanism therefor, latching mechanism comprising a main latch for releasably restraining said operating mechanism in closed position and an auxiliary latch for releasably restraining said main latch in latching position, a floating lever operable to actuate said auxiliary latch, energy storing means biasing said floating lever in tripping direction, a light-load latch for releasably restraining said floating lever against tripping operation, electro-responsive means for operating said light-load latch to release said floating lever, and means operable upon movement of said operating mechanism to open position to permit said energy storing means to relatch said floating lever.

12. In a circuit breaker including operating mechanism therefor, latching mechanism comprising a main latch for releasably restraining said operating mechanism in closed position and an auxiliary latch for releasably restraining said

main latch in latching position, a floating lever operable to actuate said auxiliary latch, energy storing means biasing said floating lever in tripping direction, a light-load latch for releasably restraining said floating lever against tripping operation, electro-responsive means for operating said light-load latch to release said floating lever, and means operable upon movement of said operating mechanism to open position to permit said energy-storing means to relatch said floating lever, said means being operable upon closing movement of said operating mechanism to store energy in said energy storing means.
